UNITED STATES PATENT OFFICE

2,500,250

SANITARY PILLOWSLIP AND SWEAT GUARD
THEREFOR

Alvin Hill, Los Angeles, Calif., assignor of forty-nine per cent to M. Langway and W. M. Bonds, both of Los Angeles, Calif.

Application July 25, 1947, Serial No. 763,683

4 Claims. (Cl. 5—339)

1

The present invention relates to a sanitary pillowslip and a sweat guard therefor and it consists in the combinations, constructions and arrangements of parts herein described and claimed.

It is an object of the present invention to provide a novel pillowslip and a sweat guard therefor.

Another object of the invention is the provision of a pillowslip and sweat guard of novel construction and which will be inexpensive to manufacture and effective and efficient in its operation.

A further object of the invention is the provision, in a device of the character referred to, of a sanitary pillowslip.

A still further object of the invention is the provision of novel means for the prevention of sweat permeation of a pillow and its associated parts.

Other and further objects of the invention will become apparent from a reading of the following specification taken in conjunction with the drawings, in which:

Figures 1 to 4, inclusive, are perspective views of certain elements of the invention and illustrating the method of their assembly.

Figure 5 is a perspective view of a pillowslip constructed in accordance with the teachings of the invention and showing a pillow partly inserted therein.

Figure 6 is a perspective view of the pillowslip with a sweat guard forming a part of the invention partly inserted therein, and

Figure 7 is a perspective view of a completely assembled embodiment of the invention.

Generally, there is provided a pillowslip formed of a cardboard backing member to which is sewed a plurality of sheets of soft, flexible, waterproof paper provided with perforations whereby the same may be readily removed one at a time as used. The whole is assembled in the form of a pillowslip with the perforated sheets upon the outer sides. Provision is made for a sweat guard adapted to be inserted between the outer sheet of paper and the remainder. The slip and the guard are provided with pairs of registering openings whereby laces may be inserted to retain the assembled elements in proper relative positions.

Referring now more particularly to the drawings, there is shown therein a pillowslip having a base member 10 preferably formed of cardboard upon which is mounted a plurality of sheets of thin, flexible and waterproof paper 11. 55

2

The base and the paper sheets are of sufficient size to form both sides of a pillowslip when folded, as indicated in Figure 1. The folded edge 12 and the contiguous sides are then sewn, as indicated at 13, the paper having been previously perforated at 14 adjacent the position of the stitches 13.

Midway of each of the sides of the folded and thus assembled pillowslip there is provided a pair of openings 15.

A sweat guard is also provided and consists of a body 16 of preferably light, pliable plastic material and a frame formed of strips 17 of stiffened material. The frame is provided with a pair of openings 18 in each side and each end, which openings are adapted to register with the openings 15 when the guard is positioned in the slip.

When so positioned between the outermost sheet 11 and the remainder of the slip and a pillow 20 has been inserted in the pillowslip, laces 19 may be inserted in the pairs of openings 15 and 18 to tie the assembled parts together in proper relative positions.

It will be seen that when the assembled device 25 is so used, perspiration is prevented from contaminating any of the sheets 11 except the outer one in contact with the user's head and that, after such use, the top sheet 11 may be easily removed by tearing the same along the lines of perforations 14 and the assembly then turned over and the guard inserted in a similar position upon the then upper side whereupon, when the laces are again tied, the device is ready for reuse.

While but one form of the invention has been shown and described herein, it will be readily apparent to those skilled in the art that many minor modifications may be made herein without departing from the spirit of the invention or the scope of the appended claims.

What is claimed is:

40 1. A device of the character described including, in combination, a pillowslip having a base of cardboard, a plurality of removable perforated sheets stitched to the outer faces thereof and a sweat guard of moistureproof material removably inserted between the outermost sheet and the remainder of the device.

2. A device of the character described including, in combination, a pillowslip having a base of cardboard, a plurality of removable, flexible, absorbent perforated sheets stitched to the outer faces thereof and a sweat guard of moistureproof material removably inserted between the outermost sheet and the remainder of the device.

50 3. A device of the character described compris-

ing, in combination, a pillowslip having a plurality of removable sheets of paper on the outer faces thereof and having a pair of openings at each side and at each end thereof, a sweat guard of moistureproof material removably inserted between the outermost sheet and the remainder of the device and having a pair of openings at each side and at each end thereof and said openings being registered with the openings in the pillowslip when the guard is positioned therein and a lace inserted in each of said pairs of registered openings.

4. A device of the character described comprising, in combination, a pillowslip having a base of cardboard, a plurality of removable sheets of perforated paper on the outer faces thereof and having a pair of openings at each side and at each end thereof, a sweat guard of moistureproof material removably inserted between the outermost sheet and the remainder of the device

and having a pair of openings at each side and at each end thereof and said openings being registered with the openings in the pillowslip when the guard is positioned therein and laces inserted in each of said pairs of registered openings.

ALVIN HILL.
